UNITED STATES PATENT OFFICE

2,553,634

ADJUSTABLE DOOR SUPPORTING CRANK
ARMGeorge E. Dath, Mokena, Ill., assignor to W. H.
Miner, Inc., Chicago, Ill., a corporation of Dela-
ware

Application August 21, 1948, Serial No. 45,477

3 Claims. (Cl. 16—105)

1

This invention relates to improvements in supporting crank arms for sliding doors of railway cars, and more particularly to means for adjusting such crank arms to raise or lower the height of the door to properly align the same with the door opening.

Other objects of the invention will more clearly appear from the description and claims herein-after following.

In the accompanying drawings forming a part of this specification, Figure 1 is a front elevational view, partly broken away, of the side wall of a railway car provided with a door opening and a sliding door for closing the opening, illustrating my improvements in connection therewith. Figure 2 is an enlarged front elevational view, partly broken away, of the door supporting crank arm and its bearing bracket, at the left hand lower corner portion of the door, as shown in Figure 1. Figure 3 is a vertical sectional view, corresponding substantially to the line 3—3 of Figure 2. Figure 4 is a horizontal sectional view, corresponding substantially to the line 4—4 of Figure 2. Figure 5 is a broken view, similar to Figure 3, but showing the door supporting crank member in elevation and illustrating the manner of application of the adjusting shims. Figure 6 is a view, similar to Figure 3, partly broken away, showing a different position of adjustment of the door supporting crank member.

In said drawings, 10 indicates the side wall of a railway car, provided with a door opening 11, closed by a sliding door 12, supported by the usual front and rear crank members 13 and 14 journaled in carriers 15—15 slidable on a lengthwise extending track 16. The sliding door 12 is further provided with the usual lever actuated rotary operating bar 17, having keeper engaging means 18 thereon, engageable with a fixed keeper 19.

As is the usual practice, the operating bar 17 has a driving connection with the rear crank member 14 to produce intermittent rotation of the same, coordinated with the operation of the keeper engaging means to move the door into and out of the door opening. The crank members 13 and 14 are of the usual design, having crank arms 20—20 journaled at their outer ends in the carriers 15—15 and provided with upstanding cylindrical shafts 21—21 at their inner ends journaled on the door.

In carrying out my invention I provide front and rear bearing brackets A and B on the door 12 in which the shafts 21—21 of the crank arms 20—20 of the front and rear crank members are journaled. The bearing brackets A and B are of similar design, with the exception that the rear

2

bracket B is relatively wider than the bracket A and is provided with bearing means in addition to the bearing means for the shaft 21 for rotatably supporting the operating bar 17.

The bearing bracket A comprises a back plate 22 and an overlying cover plate 23. The cover plate 23 has laterally projecting securing flanges 24—24 at opposite sides and a central, forwardly projecting section of U-shaped transverse cross section forming a bearing sleeve member 25. The back plate 22 has laterally projecting flanges 26—26 and top and bottom, forwardly projecting bearing lugs 27—27 which extend into the U-shaped bearing sleeve member 25 of the cover plate 23. The lugs 27—27 present vertically extending, transversely concave bearing surfaces 28—28 opposed to the concave inner wall of the sleeve member 25 and forming, with the wall of said sleeve, complete bearing members in which the shaft 21 is rotatably journaled. The flanges 24—24 of the cover plate 23 overlie the flanges 26—26 of the back plate 22 and have their outer edges turned backwardly or inwardly, as indicated at 29—29, to overlie the vertical outer edges 25 of the flanges 26—26, as clearly shown in Figure 4. The bearing bracket A is fixed to the door 12 by bolts 30—30 extending through suitable openings in the cover and back plates 23 and 22 of said bracket, and through the door. Adjacent its upper end, the sleeve member 25 of the cover plate 23 is enlarged, as indicated at 31, to accommodate a cylindrical enlargement 32 formed on the shaft 21. This enlarged portion of the sleeve 25 is of considerably greater height than the vertical dimension of the enlargement 31 of the shaft 21, thus providing for upward and downward displacement of the shaft in the bracket A. The front wall of the sleeve member 25, immediately above the enlarged portion 31 thereof, is horizontally slotted, as shown, to provide an opening 33 through which spacing shims may be inserted.

The sleeve member 25, which is open at the bottom, is closed at the top by a relatively heavy, horizontal wall 34 extending inwardly from the front wall of said sleeve in overlapping relation to the back plate 22.

One or more adjusting shims in the form of discs are interposed between the upper end of the shaft 21 and the top wall 34 of the sleeve member 25 to effect adjustment of the height of the door, one such shim, which is indicated by 35, being shown in Figure 3, and three such shims, which are indicated by 36, 37, and 38 being shown in Figure 6. These dislodge shims 35, 36, 37, and 38 are insertable within the sleeve 25 through the opening 33 thereof, this opening being of ample

size to freely admit the shims, one at a time, when the shaft 21 is lowered to clear said opening, as illustrated in Figure 5. As shown in Figure 3, when the shim 35 is in place, the bracket A is supported on the shaft 21 by the wall 34 thereof, which bears on the shim 35, which in turn bears on the upper end of the shaft 21. To adjust the height of the door 12 to a lower level, a shim of lesser thickness than the shim 35 may be used. To raise the door 12 to a higher level than that illustrated in Figure 3, two, three, or more shims may be employed, as for example, three shims 36, 37, and 38, as shown in Figure 6. The shim 35 shown in Figure 3, and the shims 36, 37, and 38 shown in Figure 6 are effectively confined within the upper end of the sleeve member 25 of the bearing bracket A by the upper end portion of the shaft 21, which, as shown, blocks the opening 33. In making any change in adjustment of the height of the door, the door is raised until the upper end of the shaft 21 clears the opening 33 of the bracket A, that is, until the lower wall of the opening reaches a point above the upper end of the shaft. The proper number of shims of the proper thickness to support the door at the required level are then selected and placed within the sleeve member 25 above the shaft 21 by inserting the same, one at a time, through the opening 33. The door 12 is then lowered to rest on the shaft 21, supported by the shim or shims interposed between the upper end of said shaft and the wall 34 of the bearing bracket.

The portion of the rear bearing bracket B, which accommodates the shaft 21 of the rear crank member 14, is similar in construction to the portion of the front bearing bracket A, which accommodates the shaft 21 of the front crank member 13, and is provided with an opening 39 similar to the opening 33 through which the spacing shims are insertable.

I claim:

1. An adjustable supporting means comprising a bracket adapted to be fixed to an object to be supported, a crank arm adapted to be swingingly supported at its outer end and having a vertically extending shaft at its inner end, said bracket including a vertically disposed bearing sleeve into which the shaft extends and is longitudinally slidible, said sleeve being closed at its upper end by a transverse wall, and spacing means comprising at least one shim between said upper end of said shaft and said wall, said spacing means resting on said upper end of said shaft, and said transverse wall resting on said spacing means to support said bearing sleeve on said shaft, said sleeve having an opening in the side wall thereof of a size to admit said shim edgewise, said opening being spaced a distance below said transverse wall which is greater than the height of said

spacing means, whereby said shaft projects upwardly past said opening to close the same in the assembled condition of the parts.

2. In an adjustable supporting means, the combination with a bracket adapted to be fixed to an object to be supported; of a crank arm adapted to be swingingly supported at its outer end, said crank arm having a vertically extending shaft at its inner end, said bracket including a vertically disposed bearing sleeve into which the shaft extends and is longitudinally slidible, said sleeve being closed at its upper end by a transverse wall; and spacing means comprising a stack of superimposed shims between said upper end of said shaft and said wall, said spacing means resting on said upper end of said shaft, said transverse wall resting on top of said spacing means to support said bracket on said shaft, said sleeve having an opening in the side wall thereof through which said shims are insertable, one at a time, in edgewise direction, said opening being spaced a distance below said transverse wall which is greater than the height of said spacing means, whereby said shaft projects past said opening to close the same in the assembled condition of the parts.

3. In an adjustable supporting means, the combination with a bracket adapted to be fixed to an object to be supported; of a vertically extending shaft engaged at its upper end with said bracket, said bracket including a vertically disposed bearing sleeve into which the upper end of said shaft extends and is longitudinally slidible, said sleeve having a transverse wall at its upper end closing the same; and spacing means comprising at least one shim, said spacing means being interposed between said upper end of said shaft and said transverse wall, said spacing means resting on said upper end of said shaft, said transverse wall resting on top of said spacing means to support said bracket on said shaft, said sleeve having an opening extending through the side wall thereof of a size to admit said shim in edgewise direction, said opening being spaced a distance below said transverse wall which is greater than the height of said spacing means, whereby said shaft projects upwardly past said opening to close the same in the assembled condition of the parts.
